ALARM DEVICE FOR INTERNAL-
COMBUSTION ENGINESLloyd Ballard Gore, Vancouver, British Columbia,
Canada

Application March 7, 1944, Serial No. 525,383

7 Claims. (Cl. 200—83)

This invention relates to improvements in alarm device for internal combustion engines and the objects are to provide a simple and effective device for this purpose to better perform the function required of it.

The improvement relates to the type of device in which the oil pressure is designed to operate against a spring controlled diaphragm whose movement is caused to control a switch which, in turn, controls an electrical alarm device.

Further objects of the invention are to improve the construction of the diaphragm-containing member and means for supporting and mounting the contact points and protecting them from interference. The invention consists essentially of the improved construction and arrangement of parts as hereinafter described in detail in the accompanying specification and drawing.

In the drawing:

Figure 1 is a section elevation of an embodiment of the invention;

Figure 2 is a sectional plan on the line 2—2 of Figure 1;

Figure 3 is a sectional plan on the line 3—3 of Figure 1;

Figure 4 is a diagrammatic view illustrating the circuit connections.

In the drawing like characters of reference indicate corresponding parts in all the figures.

Referring to the drawing A indicates the body portion of the device in which the diaphragm B is mounted, the body portion comprising a lower tubular sleeve section 10 and an upper larger cylindrical section 11 containing the diaphragm chamber 12. The diaphragm B, which may be conveniently made of thin spring metal, extends over the chamber 12, being held in position by means of a ring 13 held in place by a plurality of screws 14.

Extending through the diaphragm is a stem C, partially screw-threaded, and held with respect to the diaphragm by nuts 15 and 16 on opposite sides of the diaphragm. The stem is adapted to control the switch D mounted in a switch block 17 on top of the body portion having a peripheral flange 18 which extends over the side of the ring 13 and hold the block in place.

The switch D includes a spring contact member 19 mounted on a supporting block 20 countersunk in block 17 and connected to a terminal member 21 which extends through the block 17 and is provided on the exterior with a binding post 22. The spring contact member D carries a contact point 23, preferably of tungsten steel, adapted to engage a corresponding point 24 car-

ried on a supporting block 25 countersunk in the block 17 and connected to a contact member 26 having an exterior binding post 27. Contact members 21 and 26 are preferably firmly soldered to the blocks 20 and 25 so that they will remain firmly in place.

The stem C carries a disc-like tappet member 28 at its upper end designed to engage the upper end of the contact point 23 on the spring contact member 19 whereby the contacts are forced together when the tappet member is in lowermost position. Associated with the stem C is a spiral spring 29 tending to force the same to lowermost position. This spring extends within a cylindrical recess 30 in the sleeve 10 abutting at one end the base 31 of the recess, and at the other the ring 32 extends around the sleeve, fitting closely to the walls of the outer enlarged portion 33 of the recess. The ring 32 is held in adjusted position on the stem by means of nuts 34 and 35 which engage the screw-threaded end of the sleeve. The inner nut is separated from the ring 32 by one or more washers 36 by which the spring pressure may be adjusted.

To prevent tampering with the switch a cover chamber E is provided adapted to extend over the parts of the switch block 17, the cover being maintained in position by screws 38 which extend through it into the switch block. In order to prevent tampering with the switch a seal 37 may be provided connected to one of the screws 38 and to a screw or projection 39 on the cover.

In the circuit diagram in Figure 4, F represents an internal combustion engine, G a pump and H the oil circulating system including a gauge 39. I indicates an alarm device of the form shown in Figures 1—3, the terminals from which are connected to an electric circuit 40 including a battery 41, an audible signal 42 such as a bell and a light signal 43 and a switch 44. The switch 44 is so positioned that it will be closed when the throttle is open during the starting of the engine. This completes the circuit causing the light 43 to be illuminated and the bell 42 rung until the oil pressure reaches normal, when the contacts 23 and 24 are separated by the pressure on the diaphragm B on axial movement of the stem moving the tappet member 28 upwardly away from the spring contact member 19. At any time when the pressure drops below normal the signal will again be set in operation. The control device I is conveniently connected to the oil line between the pump and the engine, the oil having access to the chamber 12 through passages 45 and 46 in the tubular portion 10.

Although the alarm device referred to is described in connection with the lubricating system of an internal combustion engine, it will be obvious that it may be used on any piece of machinery where pressure lubrication is employed. Furthermore, it will be observed that as the pressure enters the chamber 12 through the ports 45 and 46, the pressure of the oil will compress the air in the ports and chamber, with the result that the oil never comes in contact with the diaphragm B. This is an important advantage since the viscosity of the oil will not affect the movement or resiliency of the diaphragm. Where oil has an opportunity to contact with the diaphragm, the variation of the viscosity of the oil will effect the sluggishness or otherwise of the diaphragm.

Various modifications may be made in this invention without departing from the spirit thereof or the scope of the claims, and, therefore, the exact forms shown are to be taken as illustrative only and not in a limiting sense, and it is desired that only such limitations shall be placed thereon as are disclosed in the prior art or are set forth in the accompanying claims.

What I claim as my invention is:

1. An alarm system for use with fluid pressure systems, comprising a chamber, a diaphragm dividing said chamber, means for admitting fluid to one end of said chamber, a stem passing through said diaphragm and fixed thereto, a switch block defining one end of said chamber, one end of said stem passing through said switch block and having fixed on it a member adapted to operate an electrical switch mounted between said switch block and said member upon movement of said diaphragm due to changes of fluid pressure in said chamber, said electrical switch comprising at least two terminals connected in an electrical circuit and carried on said switch block, and means for making an electrical contact between said terminals, said means being urged by spring pressure to open said circuit and being engaged by said member and actuated against said spring pressure to make said electrical contact and close said circuit.

2. The device as claimed in claim 1 in which the switch comprises terminals countersunk in the switch block having external binding posts.
3. The device as claimed in claim 1 in which 5 the switch comprises a spring contact member connected to one of said terminals and having a tungsten point adapted to engage a corresponding contact point mounted in the switch block in connection with the other of said terminals.
- 10 4. An alarm system as defined in claim 1 comprising a cover enclosing said member, said switch block and said electrical switch.
5. The device as claimed in claim 1 in which a cover is provided extending over the switch 15 and in which sealing means extend between the cover and switch block.
6. An alarm system for use with fluid pressure systems comprising a chamber, a diaphragm dividing said chamber, a switch block defining one 20 end of said chamber, means for admitting fluid to the other end of said chamber, a stem passing through said diaphragm and affixed thereto, one end of said stem passing through said switch block and carrying means for operating an electrical switch, and means for adjusting the pressure 25 at which the alarm operates comprising an elongated recess surrounding a portion of said stem, a coil spring housed in said recess and around said stem, and means on said stem adapted to compress said spring against the end of said recess nearer to said diaphragm to urge said stem in a direction opposite to that effected by said diaphragm under influence of fluid pressure in 30 said chamber, said means adapted to compress said spring being adjustable along the length of said stem to vary compression of said spring.
- 35 7. An alarm system for use with fluid pressure systems as defined in claim 6, comprising a sleeve carried by said stem and moveable axially thereon, and at least one nut threaded on a portion of said stem, said sleeve engaging said nut at 40 one end and at the other engaging said spring.

LLOYD BALLARD GORE.
